TWO-PIECE BOX BODY

Roy K. Wilson, Jacksonville, Fla., assignor to St. Regis Paper Company, Jacksonville, Fla., a corporation of New York

Filed July 6, 1959, Ser. No. 825,344
2 Claims. (Cl. 229—15)

This invention relates to containers and more particularly to a two-piece compartmented box body which is formed from blanks composed of corrugated or solid paper materials such as fiberboard, paperboard, boxboard and the like.

A general object of the invention is to provide an improved box body.

Another object is to provide a two-piece compartmented box body which is durable in construction, easy to assemble from blanks and which is simple in design.

Still another object is to provide a partitioned box body for a container which may be filled with a commodity that tends to settle and thereby take up less space, such as tomatoes, and which is provided with telescoping walls that are adjustable in height in accord with the level of the commodity in the container.

Another object is to provide a tray arranged to hold together a folded over sleeve of figure-8 shape and where the sleeve in turn holds the flanges of the tray in position.

The novel features which are believed to be characteristic of this invention are set forth with particularity in the appended claims. The invention itself, however, both as to its organization and method of operation, together with further advantages thereof, may best be understood by reference to the following description taken in connection with the accompanying drawings, in which:

FIG. 1 is an exploded perspective view of a box which includes a two-piece box body and a cover therefor;

FIG. 2 is a plan view of a blank from which the cover of the box illustrated in FIG. 1 is formed;

FIG. 3 is a plan view of a blank from which the tray of the box body illustrated in FIG. 1 is formed;

FIG. 4 is a plain view of a blank from which the outer shell of the box body illustrated in FIG. 1 is formed;

FIG. 5 is a perspective view of the outer shell shown in FIG. 1, illustrating a form which the shell takes during an intermediate stage of assembly;

FIG. 6 is a perspective view of the assembled box shown in FIG. 1; and

FIG. 7 is a sectional view taken along the line 7—7 of FIG. 6.

The box as shown in FIG. 1 is made up of a cover 1 and a two-piece box body which is generally designated at 2.

The body 2 of the box includes a corner cut flanged tray 3 which functions as a bottom supporting member for commodities carried in the box and an outer shell 4 which telescopes over the upstanding flanges or walls of the tray.

The tray 3 has opposite end wall panels 5 and 6 and opposite side walls 7 and 8. The side walls 7 and 8 are each interrupted by a vertical slot, as at 13 and 14 which divide the respective side walls into separate panels as at 9 and 10, and at 11 and 12.

The shell 4, on the other hand is composed of a pair of integrally attached open ended sleeves 15 and 16 which are each provided with opposite end panels as at 17 and 18, and at 19 and 20, and opposite side panels, as at 21 and 22, and at 23 and 24. End panels 18 and 19 function as a double walled partition 28 which divides the shell into two compartments, 25 and 26, that are respectively defined by the sleeves 15 and 16. The only physical link between the sleeves is along the top edge 27 of the partition 28. When the shell is telescoped over the

2

walls of the tray, the sleeves 15 and 16 function as bands that support the side and end panels of the tray 3 against outwardly directed forces exerted thereagainst.

It will be noted that end panels 17 and 20 of the shell 4 are provided with horizontally extending hand holes 29 and 30 which are spaced below the respective upper edges of the sleeves. The end wall panels 5 and 6 of the tray 3 are provided with internally cut downwardly extending tongues 31 and 32 respectively. The tongues 31 and 32 are so cut from the end panels as to be provided with enlarged lower ends 33 and 34 which are the same size as the hand holes 29 and 29 respectively and which are arranged to register therewith and pass through the respective hand holes when the shell 4 is fully telescoped over the tray 3. The tongues engage the end panels when the shell is thereafter raised and accordingly provide a means for linking the shell 4 and tray 3 together. The cut which forms the tongue in each case is such, as exemplified by the cut in end panel 6, that the tongue 32 is hinged to the panel 6, as at 35, at a lesser distance from the top edge 36 of the panel than the distance from the bottom edge 37 of the cooperating hand hole 29 to the top edge of end panel 17. This arrangement provides a loose locking attachment between the shell 4 and tray 3 and enables the respective walls thereof to move relatively vertically while still being locked together.

Each of the end panels 17 and 20 of the shell 4 also have another slot, as at 38 and 39, which is spaced above the adjacent hand hole, therein. As will be shown, these slots 38 and 39 cooperate with tongues in the end flanges 40 and 41 of the cover 1 and provide a means for securing the cover 1 on the box body 2.

The blank 1' from which the cover is formed is shown in FIG. 2. The blank 1' is generally rectangular in shape and has longitudinally scored lines 42 and 43 along which the top portion 44 of the cover and the side flanges 45 and 46 thereof are integrally attached. Each of the side flanges 45 and 46 has opposite end flap extension, as at 47 and 48, and at 49 and 50', respectively, which are integrally connected along scored lines, as at 50, 51, 52 and 53 to the respective side flanges.

The end flanges 40 and 41 of the cover are integrally connected to the top portion 44 along transverse scored fold lines 54' and 55', and are separated from the adjacent end flaps 47, 48, 49 and 50' of the side flanges by end cuts 54, 55, 56 and 57 respectively. Each of the end flanges 40 and 41 is composed of outer and inner flange portions which are respectively inwardly and outwardly of each other in the blank form as for example, outer portions 58 and 59 and inner portions 60 and 61. The outer and inner portions of each end flange are integrally attached along a pair of parallelly spaced fold lines, as at 62 and 63 for end flange 40 and at 64 and 65 for end flange 41. The fold lines, as for example fold lines 62 and 63, are sufficiently spaced in parallel to enable the adjacent end flaps as for example end flaps 47 and 49 to extend between the inner flange and outer flange portions, when the cover is in the assembled condition.

The inner flanges 60 and 61 are provided with respective tabs as at 66 and 67, and at 68 and 69, which project outwardly when the blank is in the unfolded condition. The top portion 44 of the cover is provided with slots as at 70 and 71, and at 72 and 73, which are adapted to receive the respective tabs and to cooperate therewith in maintaining the cover in an assembled condition when the blank 1' is folded. It will also be noted that the inner flanges 60 and 61 are provided with elongated internal curvilinear cuts 74 and 75 which provide outwardly extending tongues 76 and 77 when the cover is in the blank form. These tongues 76 and 77 project into and cooperate with slots 38 and 39 of shell 4 when the cover is assembled and telescoped onto the box body. The

opposite ends of the inner flanges 60 and 61 are cut away to form slots 106, 107, 108 and 109 at the outer end extremities, of cuts 54, 55, 56 and 57 respectively. These slots are of substantially the same width as the thickness of the blank 1' to enable the inner portion of the flange to extend laterally between the side flanges 45 and 46 when the cover is assembled.

The cover 1 is assembled by first bending the side flanges 45 and 46 along scored fold lines 43 and 42 until the flanges 45 and 46 are perpendicular to the top portion 44 of the cover. Thereafter the end flaps 47, 48, 49 and 50' are bent inwardly along the respective fold lines 50, 51, 52 and 53 until the flaps are perpendicular to their respective side flanges. Next the end flanges 40 and 41 are folded along respective fold lines 54' and 55' until outer flanges 58 and 59 are in abutting face to face relationship with the end flaps 47 and 49, and 48 and 50', respectively. Next the inner flange portions 60 and 61 are folded inwardly and over the respective adjacent end flaps and the end tabs 66, 67, 68 and 69, inserted in their cooperating holes 70, 71, 72 and 73 respectively.

As shown in FIG. 3, the tray blank 3' is rectangular in shape with the corners cut and removed to form rectangular end panels 5 and 6 and rectangular side walls 7 and 8. End panels 5 and 6 are integrally joined to the bottom portion 78 of the tray along transverse scored fold lines 79 and 80 whereas the side walls 7 and 8 are integrally joined to the bottom portion 78 along longitudinally extending scored fold lines 81 and 82 respectively. The side walls 7 and 8 have slots 13 and 14 which are cut intermediate the respective ends of the walls thereby dividing the walls into rectangular panels 9 and 10 and rectangular panels 11 and 12 respectively. Slots 13 and 14 are of sufficient thickness to enable the double-walled partition 28 of shell 4 to extend therethrough when the box body is assembled.

The tongues 31 and 32 in end panels 5 and 6 respectively are formed by the respective cuts 83 and 84 which enable the tongues to be depressed pivotally inwardly of the respective plane of the end panels along integral hinge connections represented by broken lines 85 and 86.

The tray is formed from the blank 3' by bending the end panels 5 and 6 and side wall panels 9, 10, 11 and 12, along fold lines 80 and 79, and 81 and 82, respectively, until the panels are perpendicular to the bottom panel 78 of the tray.

The blank 4' from which the shell 4 is formed is shown in FIG. 4 and is elongated and rectangular in shape. The blank 4' is divided longitudinally into elongated symmetrical portions 87 and 88 by an elongated center cut 89 and scored fold lines 90 and 91 along the latter of which the opposite portions 87 and 88 are integrally attached. Extending transversely of the blank on both sides of the cut 89 are spaced and scored fold lines 92, 93, 94 and 95. Integrally attached partition wall panels 18 and 19 are respectively integrally attached to side panels 15 and 16 respectively along fold line 95. The side panels 15 and 16 which are separated by cut 89 are integrally attached to end panels 17 and 20 respectively along fold line 94. Panels 17 and 20 which are also separated by cut 89 are integrally attached to side panels 22 and 24 respectively along fold line 93. The cut separated side panels 22 and 24 are integrally secured to end portions 96 and 97 respectively along fold line 92.

It will be noted that each of the end panels 17 and 20 is provided with a slot adjacent to and spaced from cut 89, as at 38 and 39, for the reception of the tongues in the cover 1. Further spaced from the cut 89 each of these panels is provided with a hand hole as at 29 and 30. Respective hand holes 93 and 99 are also provided in the panels 18 and 19 which form the double-walled partition 28.

To assemble the shell 4, the blank is first folded along lines 92, 93, 94 and 95, as shown in FIG. 5 and the

opposite ends 100 and 101 of the blank are joined in end abutting relationship by means of suitable adhesive type tape 102.

Thereafter panels 18 and 19 and their respective end portions 96 and 97 are folded along lines 91 and 90 respectively until the panels 18 and 19 are in face to face relationship as shown in FIG. 1. The outer shell may be then telescoped over tray 3, and cover 1 telescoped over the top of the shell as shown in FIG. 6.

Referring now to FIGS. 6 and 7, in attaching the outer shell 4 to tray 3, the shell 4 is first shoved down upon the tray 3 until the bottom end 103 of the partition 28 contacts the bottom portion 78 of tray 3. In this position, the hand holes, as for example hole 29, are in alignment with the enlarged portions of the tongues, as for example the enlarged portion 34 of tongue 32. The tongues in the end panels of the tray may then be pressed outwardly through the respective hand holes in the shell 4. Once the tongues are pressed outwardly, the shell 4 may then be raised relative to the tray until the upper portions of the tongues as at 104 for tongue 32 engage the lower edges, as at 105, of the respective cooperating slots. With the shell in the raised position, as shown in FIG. 7, it will be apparent that the box body may then be filled and cover 1 thereafter telescoped over the upper edges of the shell 4.

FIG. 7 illustrates the locking connection between the cover 1 and shell 4. As illustrated at end flange 40, the tongue 76 in the inner flange 60 extends inwardly when the tabs, such as at 66, of the inner flange 60 are lockingly engaged in their respective slots. As such, when the cover is telescoped down upon the shell, the tongues engage the slots, as at 38, and the cover is locked in position therat. By pulling outwardly on the end flanges, the tongues may be released from the slots and the cover lifted from the shell.

As the commodities contained in the box body settle and take up less space therein, the outer shell 4 may be pressed downwardly over the tray 3 since the walls of the box body are adjustable in height to the extent that the connections between the tray 3 and sheet 4 permit relative vertical movement.

The box body has a further advantage in that it may be employed for commodity displaying purposes in stores and the like either as is or in a severed condition. For example, when the cover 1 is removed, the commodities in the respective compartments may be viewed in the two compartment container. When desired, the box body may be separated into two distinct portions by cutting the bottom portion 78 of the tray transversely between the tray side wall slots 13 and 14 and by cutting the partition along the top edge 27.

While only a certain preferred embodiment of this invention has been shown and described by way of illustration, many modifications will occur to those skilled in the art and it is, therefore, desired that it be understood that it is intended in the appended claims to cover all such modifications as fall within the true spirit and scope of this invention.

What is claimed as new and what it is desired to secure by Letters Patent of the United States is:

1. A two-piece compartmented box body comprising a tray having a bottom panel and upstanding end flanges and side flanges connected thereto, the side flanges at each side being bisected by a substantially uniform slot midway between the ends thereof extending from the top to the bottom of the flange thereby dividing the flange into two portions, and a double compartment shell telescoped over said tray, said shell comprising a pair of rectangular side-by-side sleeves open at top and bottom and having a common wall, said common wall being disposed in and fittingly supported within said slots thereby forming a partition across said tray, said common wall extending outwardly through said slots in said side flanges of said tray, and said sleeves being each telescoped over

a respective end wall and the thereto adjacent one of said portions of each said side flange.

2. A two-piece box body comprising, a rectangular sleeve having three of its side walls severed midway between its ends and having its fourth wall folded back on itself along a fold line midway between its ends thereby to form an open top and bottom 8-shaped shell comprising two side-by-side open sleeve elements, a one-piece corner cut out tray including a bottom panel, an upstanding end flange at each end of the bottom panel and a pair of upstanding side flanges along each side of said bottom panel, each said side flange of each pair extending from the center of the side edge of the bottom panel toward a respective end thereof, said shell being telescoped over said end flanges and said side flanges with a respective 15 one of said end flanges and a respective one of each pair

of said side flanges fitted telescopingly into the open end opposite said fold line of each respective said sleeve element.
